UNITED STATES PATENT OFFICE.

CLYDE T. ELDREDGE, OF SAN FRANCISCO, CALIFORNIA.

HIGHWAY TRACK.

1,403,943.

Specification of Letters Patent. Patented Jan. 17, 1922.

Application filed June 1, 1921. Serial No. 474,110.

To all whom it may concern:

Be it known that I, CLYDE T. ELDREDGE, a citizen of the United States, and resident of San Francisco, county of San Francisco, 5 and State of California, have invented a new and useful Highway Track, of which the following is a specification.

The present invention relates to improvements in highway tracks and its object is to 10 provide a steel track in concrete roads adapted to be fit into the road bed without causing the concrete surrounding it to chip. Another object is to provide a track in combination with a system of reinforcing steel 15 rods adapted to firmly combine track and road bed into one inseparable mass and at the same time to fortify the concrete so that the whole will resist severe strains brought to bear on it. Another object is to provide 20 a track grooved in such a manner that the tire of an automobile will not slip on the same and is practically geared to the same. Other advantages and objects will appear 25 as the description proceeds.

25 While in the following description I shall explain my invention with reference to concrete road beds I do not wish to confine myself thereto and wish to be protected on the general principles rather than the one 30 embodiment of the same.

One embodiment of my invention is illustrated in the accompanying drawing, in which Figure 1 is a perspective view of road bed having my tracks secured in the same, 35 Figure 2 a plan view of my track and reinforcing means used in connection therewith, Figure 3 a cross section through the road bed along line 3-3 of Figure 2, Figure 4 an enlarged end view of a single unit of the 40 track showing connecting means for the adjoining unit, and Figure 5 a fragmentary detail plan view of a plate forming the top of my track.

Referring to the drawing in detail it will 45 be seen that the road bed 1 is made of a heavy layer of concrete 2 with two rails 3 embedded therein at a distance from each other corresponding to the width of the ordinary vehicle. The principal supporting 50 part of each rail is an I-beam 4 standing on edge with its bottom extending into the concrete bed a little more than half-way, and its top not quite reaching the top of the concrete but leaving space for an additional plate 6. 55 The latter is considerably wider than the top of the I-beam and, when secured to the same

by the countersunk rivets 7, is about flush with the top of the concrete road bed. This plate 6 is not very heavy as compared with the thickness of the road bed. To convey 60 the proper idea, without limiting myself thereby, I wish to state that I propose to use a sheet of steel about $\frac{1}{8}$ of an inch thick fortified by longitudinal ribs 10. I find that in this manner, that is, by using a comparatively thin plate of steel to provide the margin for a heavier rail, I can eliminate the chipping of the concrete to such an extent that it does not impair the usefulness of the 65 tracks.

To prevent skidding of rubber tires on the rails I provide small diagonal grooves 8 arranged parallel and in zig-zag lines on the surface of the plate. The grooves are not deep and are placed close enough so that the 70 tire of an automobile will grip a new one before letting go of the last one. The corners of the grooves are rounded off, as shown particularly well in Figure 5, so that they do not cut into the tires.

The rails which are made and shipped in pieces of certain lengths, are secured to each other by angle irons 9 fitted into the lower corners of the I-beams and plates 11 fitted to the bottom of the same. The holes 15 75 receiving the bolts connecting them are slightly slotted to allow for expansion. The plates 6 are secured to each other by ribbed strips 12 connecting their overhanging margins.

It will be noted that my rails do not penetrate the road bed altogether so as to cut the same into distinct units, but are embedded in the same so that a sufficient layer of concrete is left under the rail to properly 85 support the same and to constitute a means for binding the road bed into one solid structure. It is assisted herein by a system of reinforcing rods 14 consisting of longitudinal members 16 and transverse members 17. 90 The transverse members penetrate the webs of the rails at a point somewhat below their centers and are secured to the transverse members in any desired manner. They should be of square or angular cross-section, 95 preferably twisted so as to ally itself with the concrete as closely as possible.

It will be seen that in this manner a track may be embedded into a concrete or similar road bed which is for all practical purposes 100 an integral part of the same, which serves 110 simultaneously to reinforce the road bed and

is so constructed that chipping of the road bed will be eliminated altogether.

I claim:

1. In a concrete road bed, a metal track comprising two I-beams embedded in the road bed on edge in related distance from each other, and a comparatively thin metal plate resting on each I-beam having marginal portions extending beyond the same and making contact with the concrete.
2. In a concrete road bed, a metal track comprising two I-beams embedded in the road bed on edge in related distance from each other, and a comparatively thin metal plate resting on each I-beam having marginal portions extending beyond the same and making contact with the concrete, said marginal portions being fortified by longitudinal ribs.
3. In a concrete road bed, a metal track comprising two I-beams embedded in the road bed on edge in related distance from each other, and a comparatively thin metal plate resting on each I-beam having marginal portions extending beyond the same and making contact with the concrete, said marginal portions being fortified by longitudinal ribs, and said plates being grooved so as to prevent skidding.
4. In a concrete road bed, a metal track comprising two I-beams embedded in the road bed on edge in related distance from each other, and a comparatively thin metal plate resting on each I-beam having marginal portions extending beyond the same and making contact with the concrete, said marginal portions being fortified by longitudinal ribs, and said plates being provided with parallel zig-zag grooves having overlapping extremities so as to prevent skidding.
5. In a concrete road bed, a metal track comprising two I-beams embedded in the road bed on edge in related distance from each other, and a comparatively thin metal plate resting on each I-beam having marginal portions extending beyond the same and making contact with the concrete, and transverse metal members penetrating the webs of the I-beams and reinforcing the concrete.
6. In a concrete road bed, a metal track comprising two I-beams embedded in the road bed on edge in related distance from each other, and a comparatively thin metal plate resting on each I-beam having marginal portions extending beyond the same and making contact with the concrete, and trans-
- verse metal members penetrating the webs of the I-beams and having longitudinal members connecting them for reinforcing the concrete.
7. In a concrete road bed, a metal track comprising two I-beams embedded in the road bed on edge in related distance from each other, and a comparatively thin metal plate resting on each I-beam having marginal portions extending beyond the same and making contact with the concrete, said marginal portions being fortified by longitudinal ribs, and transverse metal members penetrating the webs of the I-beams and reinforcing the concrete.
8. In a concrete road bed, a metal track comprising two I-beams embedded in the road bed on edge in related distance from each other, and a comparatively thin metal plate resting on each I-beam having marginal portions extending beyond the same and making contact with the concrete, said marginal portions being fortified by longitudinal ribs, and transverse metal members penetrating the webs of the I-beams having longitudinal members connecting them for reinforcing the concrete.
9. In a concrete road bed, a metal track comprising two I-beams embedded in the road bed on edge in related distance from each other, and a comparatively thin metal plate resting on each I-beam having marginal portions extending beyond the same and making contact with the concrete, said marginal portions being fortified by longitudinal ribs, and said plates being grooved so as to prevent skidding, and transverse metal members penetrating the webs of the I-beams having longitudinal members connecting them for reinforcing the concrete.
10. In a concrete road bed, a metal track comprising two I-beams embedded in the road bed on edge in related distance from each other, and a comparatively thin metal plate resting on each I-beam having marginal portions extending beyond the same and making contact with the concrete, said marginal portions being fortified by longitudinal ribs, and said plates being provided with parallel zig-zag grooves having overlapping extremities so as to prevent skidding, and transverse metal members penetrating the webs of the I-beams having longitudinal members connecting them for reinforcing the concrete.

CLYDE T. ELDREDGE.
